ADJUSTABLE TABLE TOP

Filed July 11, 1946

UNITED STATES PATENT OFFICE

2,500,542

ADJUSTABLE TABLE TOP

David Greene, Brooklyn, N. Y., assignor to Esmco
Auto Products Corporation, Brooklyn, N. Y., a
corporation of New York

Application July 11, 1946, Serial No. 682,829

10 Claims. (Cl. 311—37)

1

This invention relates to tables of the type and kind sometimes classified as "bed-tables," useable for any purpose in adjusting the height of a table as well as the degree of inclination of the table top. More particularly, the invention deals with articles of the character described wherein means is provided for forming pivotal supports at each side of a supporting frame for a table top so that either side portion may function as a pivot in moving the table into inclined positions, and further in retaining the table top against pivotal or swinging movement. Still more particularly, the invention deals with a common lock link for supporting the table in different angular positions on either of its pivots. Still more particularly, the invention deals with a table structure having a single manually operated means in what may be termed the leg or base frame for retaining the table supporting frame in different positions of vertical adjustment. The novel features of the invention will be best understood from the following description when taken together with the accompanying drawing in which certain embodiments of the invention are disclosed, and in which the separate parts are designated by suitable reference characters in each of the views, and in which:

Fig. 1 is a side view of a table structure made according to my invention with part of the construction broken away and in section.

Fig. 2 is a perspective view of the table as seen in Fig. 1, and on a reduced scale.

Fig. 3 is an end view of the table on a reduced scale showing the table swinging on one of its pivots in full lines, and on the other pivot, in dot and dash lines.

Fig. 4 is a section on the line 4—4 of Fig. 1, on an enlarged scale.

Fig. 5 is a section substantially on the line 5—5 of Fig. 2, on an enlarged scale, with part of the construction broken away.

Fig. 6 is a section looking in the direction of the arrows 6—6 of Fig. 2, with part of the construction broken away and in section; and

Fig. 7 is a section on the line 7—7 of Fig. 3, on an enlarged scale.

My improved table structure comprises two substantially similar frames, namely a base or leg frame 10, and a top or table frame 11. The frame 10 has a U-shaped base portion 12, the ends of which terminate in upwardly extending tubular supports 13—13' joined and braced by a cross strap 14, as clearly seen in Fig. 2 of the drawing. The frame 11 has an upper U-shaped table supporting portion 15, the ends of which

2

terminate in downwardly extending tubular portions 16 and 16' telescoping in the portions 13—13' in vertical adjustment of the frames one with respect to the other in adjusting the height of a table 17 with respect to a predetermined surface.

The tubular portions 13—13' have adjacent their upper ends, apertures 18, note Fig. 6, and the tubular portions 16—16' have vertically spaced apertures 19 adapted to register with the apertures 18 in receiving key rods 20—20' for keying and retaining the frames 10 and 11 in different positions of adjustment one with respect to the other.

15 Inner adjacent ends of the rods 20—20' are pivoted to a crank plate 21 which in turn is rotatably mounted in the strap 14 by the axis portion 22 of a handle 23. The axis portion 22 has a coil spring 24 arranged thereon, one end of 20 which is secured to the plate 21 and the other to the strap 14. The spring is so tensioned as to normally support the rods 20 and 21 in operative position, as shown in Fig. 6. By rotating the handle member 23 in the direction of the 25 arrow 25 of Fig. 6, both rods 20 and 20' are simultaneously drawn out of engagement with the apertures 19, thus freeing the frame 11 for relative adjustment with respect to the frame 10.

Struck out from the strap 14 are two rod guiding ears 26 and 26' having large apertures 27 and 27' to compensate for swinging movement of the rods while maintaining the rods at all times in alinement with the apertures 18 and 19 when in registering position. Joining the tubular portions 16—16' of the frame 11 is a strap 28 having an elongated aperture 29 in one wall of which is formed a series of longitudinally spaced notches 30. Secured to one end of the table top 17 is an L-shaped bracket 31 to which 35 is pivoted, as seen at 32, a lock link 33. The link 33 carries at its lower end a short shaft 34 having a fingerpiece or button end 35, the shank 36 of which normally fills the full width of the slot 29, including the notch offset 30, note Fig. 4.

40 The pin 34 is of reduced diameter and protrudes beyond the inner end of the link 33 and has a head 37 at its inner end. Between this head and the link 33 is mounted a coil spring 38 normally supporting the parts in the operative position shown in Fig. 4. When it is desired to adjust the table top, the fingerpiece 35 is moved in the direction of the arrow 39, Fig. 4, bringing the pin 34 into the slot 29, thus allowing the pin to move longitudinally of the slot 29 in 45 adjusting the position of the lever and the re-

sulting angular position of the table 17, one raised position of the table being shown in Fig. 3 in full lines in swinging the table on the pivot side 40 and in another position in dot-dash lines in swinging the table on the pivot side 41.

The pivot sides of the table are formed by channelled strips 42-42'. These strips extend a substantial length of the table sides and have a short outer side 43-43' notched centrally thereof, as indicated at 44-44', and a long inner side 45-45' having an elongated aperture 46-46'. The cross head portion of the channel strips 42-42' are cut out or recessed centrally, as seen at 47-47' to receive a lock and pivot forming bar 48 slidable over the lower surface of the table 17. The bar 48 has inturned U-shaped ends 49-49', the inwardly directed end portions 50-50' of which are adapted to pass into and through the apertures 46-46' and to form in conjunction with the channel strips 42-42', pivot portions or housings for the side rods 51-51' of the table supporting part 15 of the frame 11.

The end portions 50-50' of the bar 48 have upwardly struck beads 52-52' adapted to engage the rods 51-51' in retaining the table 17 in a neutral locked position upon the frame 11 and against pivotal or swinging movement when the device is utilized to maintain a flat table top. This position of the parts is indicated in Fig. 5.

In forming the pivot sides, as at 40-41 of Fig. 3, the bar 48 is moved across the table to pass the end 50 through the aperture 46 in the one instance or the end 50' through the aperture 46' in the other instance, in which operation, the beads 52-52' frictionally pass over the bars 51-51'. In other words, when the end 50 closes the channel 42 to form the pivot housing, as at 40, the end 50' is drawn free of the channel 42', leaving the bar 51' free to move out of the channel, as the side 53 of the table 17 is raised, as shown in full lines in Fig. 3. In the dotted line position of Fig. 3, the table side 54 is raised, the channel 42 is opened and the channel 42' is closed. It will thus be seen that in a simple back and forth sliding movement of the bar 48, either pivot 40-41 can be produced or the neutral position of Fig. 5 can be attained. In either pivot of the table top, the one brace and lock link 33 retains the table in the different positions of adjustment and also aids in retaining the table in the lowered or neutral position, the link 33 being then in the position shown in Fig. 2.

From the foregoing, it will be apparent that a very simple and economical structure is provided in producing the double pivotal mounting of the table top and in retaining the table top in its different positions of adjustment. Whereas a single one motion control is provided in releasing the frame 11 for adjustment with respect to the frame 10. It will also appear that the sides 53 and 54 of the table have raised cleats 55 and 56 to form supports for books, papers or other articles while the table top is in its different angular positions, and in these respects and in the use of the table, these sides may be alternately considered as front and rear sides so either side can be a front or rear, depending upon the pivotal mounting.

Having fully described my invention, what I claim as new and desire to secure by Letters Patent is:

1. In a table of the class described employing a base having a table supporting frame, said frame having spaced parallel rails, a table mem-

ber arranged upon the table frame, said table member having a pair of elongated channels adapted to receive said spaced parallel rails of said table frame, the channels having wide side wall members, said wide side wall members having transversely alined apertures therein, a pivot forming bar slidably mounted on the table member and keyed to said channels, and said bar having hook-shaped ends movable through the apertures in said walls of the channels in forming in conjunction with the channels pivotal supports for the table member upon either of said rails.

2. In a table of the class described employing a base having a table supporting frame, said frame having spaced parallel rails, a table member arranged upon the table frame, said table member having a pair of elongated channels adapted to receive said spaced parallel rails of said table frame, the channels having wide side wall members, said wide side wall members having transversely alined apertures therein, a pivot forming bar slidably mounted on the table member and keyed to said channels, said bar having hook-shaped ends movable through the apertures in said walls of the channels in forming in conjunction with the channels pivotal supports for the table member upon either of said rails, and means on the hook ends of said bar retaining the bar in neutral position and the table member against swinging movement on said rail.

3. In a table of the class described employing a base having a table supporting frame, said frame having spaced parallel rails, a table member arranged upon the table frame, said table member having a pair of elongated channels adapted to receive said spaced parallel rails of said table frame, the channels having wide side wall members, said wide side wall members having transversely alined apertures therein, a pivot forming bar slidably mounted on the table member and keyed to said channels, said bar having hook-shaped ends movable through the apertures in said walls of the channels in forming in conjunction with the channels pivotal supports for the table member upon either of said rails, means on the hook ends of said bar retaining the bar in neutral position and the table member against swinging movement on said rail, and means comprising a link pivoted to the table member and slidably pivoted to the table frame for supporting the table member in different inclined positions when swung on either of its pivots.

4. In tables of the class described employing a base having a top frame part, a table member, the top frame part having a pair of spaced parallel rails, the table member having channel strips arranged longitudinally of and housing said rails, and means movably supported on the table member and cooperating with said channel strips and said rails for forming in conjunction with said strips fixed pivotal mountings of the table member on either of said rails.

5. In tables of the class described employing a base having a top frame part, a table member, the top frame part having a pair of spaced parallel rails, the table member having channel strips arranged longitudinally of and housing said rails, means movably supported on the table member and cooperating with said channel strips and said rails for forming in conjunction with said strips fixed pivotal mountings of the table member on either of said rails, and said last named means

including means retaining the table member against swinging movement on said rails in one position of said means.

6. In tables of the class described employing a base having a top frame part, a table member, the top frame part having a pair of spaced parallel rails, the table member having channel strips arranged longitudinally of and housing said rails, means movably supported on the table member and cooperating with said channel strips and said rails for forming in conjunction with said strips fixed pivotal mountings of the table member on either of said rails, said last named means including means retaining the table member against swinging movement on said rails in one position of said means, said top frame including an elongated strap, and means movably coupled with said strap and said table member for supporting the table member in different positions of inclination with respect to either of said rails.

7. In tables of the class described employing a base having a top frame part, a table member, the top frame part having a pair of spaced parallel rails, the table member having channel strips arranged longitudinally of and housing said rails, means movably supported on the table member and cooperating with said channel strips and said rails for forming in conjunction with said strips fixed pivotal mountings of the table member on either of said rails, said last named means including means retaining the table member against swinging movement on said rails in one position of said means, said top frame including an elongated strap, means movably coupled with said strap and said table member for supporting the table member in different positions of inclination with respect to either of said rails, and said means comprising a link pivoted to the table member and slidably engaging a notched portion of said strap.

8. In tables of the class described employing a base having a top frame part, a table member, the top frame part having a pair of spaced parallel rails, the table member having channel strips arranged longitudinally of and housing said rails, means movably supported on the table member and cooperating with said channel strips and said rails for forming in conjunction with said strips fixed pivotal mountings of the table member on either of said rails, said last named means including means retaining the table member against swinging movement on said rails in one position of said means, said top frame in-

cluding an elongated strap, means movably coupled with said strap and said table member for supporting the table member in different positions of inclination with respect to either of said rails, said means comprising a link pivoted to the table member and slidably engaging a notched portion of said strap, and the coupling of the link with the notched strap comprising a spring pressed head pin locking the link on the notched strap in one position thereof.

9. In a table member of the class described, a pair of spaced table supports arranged adjacent and extending longitudinally of side edges of the table member, members extending longitudinally of side edges of the table member engaging said supports, and means adjustable transversely of the table member and cooperating with said members in forming a pivotal mounting of the table member independently on each of said supports.

10. In a table member of the class described, a pair of spaced table supports arranged adjacent and extending longitudinally of side edges of the table member, members extending longitudinally of side edges of the table member engaging said supports, means adjustable transversely of the table member and cooperating with said members in forming a pivotal mounting of the table member independently on each of said supports, and means movably coupled with the table member and said supports for adjustably supporting the table member in inclined position when pivoted on either of said supports.
